SIGNAL TRANSLATING APPARATUS

Alexis Badmaieff, Indianapolis, Ind., assignor to
Radio Corporation of America, a corporation of
Delaware

Original application June 12, 1943, Serial No.
490,614. Divided and this application April 29,
1944, Serial No. 533,333

6 Claims. (Cl. 179—100.41)

1

My present invention relates generally to systems utilizing angle modulated oscillations, and more particularly to an improved electrical signal translating device of the capacity type especially useful in connection with a system for providing frequency modulated oscillations in conjunction with a balanced transducer input, the present application being a division of my copending application Serial No. 490,614, filed June 12, 1943, now Patent No. 2,371,373, granted March 13, 1945.

In the past, there has been shown considerable interest in frequency modulated oscillatory systems of the type wherein an oscillator and discriminator are usually a short distance apart, or even combined in one unit. Such systems have been applied to sound reproducing devices and to measuring devices. In such prior systems, an oscillator is provided with a frequency changing transducer, and the transducer is varied in response to a vibratory member thereby to frequency modulate the oscillator mean frequency. The frequency modulated energy is then fed to a discriminator circuit which is tuned to a slightly different frequency so that the oscillator mean frequency falls on one side of the discriminator's resonance curve. The discriminator converts the frequency-variable wave energy into amplitude-variable wave energy. Subsequent rectification derives the original modulating frequencies from the amplitude-variable wave energy.

I have invented a method of greatly increasing the voltage output of such a system. The method is simple and employs a minimum of elements. The method essentially comprises the concurrent frequency variation, from one modulating source, of the oscillator frequency and the discriminator resonance peak in opposite directions.

From a generic viewpoint, it may be stated that it is one of the principal objects of my invention to provide a method wherein a properly constructed, balanced transducer is employed to vary the oscillator and discriminator circuit tuning in opposite directions, or in opposite phase relation, simultaneously.

It is an important object of my present invention to provide a frequency modulated ("FM" for brevity hereinafter) oscillator feeding into a discriminator whose resonance peak is subjected to concurrent FM action, the two frequency modulations being 180 degrees out of phase whereby the discriminator voltage output will be twice as great as would be the case if only one of said FM actions had been employed.

2

The two forms of FM may be provided simply in an oscillator-discriminator network by employing a balanced transducer, more specifically a push-pull condenser, as the modulating device. One side of the condenser can then be connected across the oscillator coil, while the other side is connected across the discriminator coil. Hence, if the grounded center plate is moved either way, the directions of the frequency changes of the oscillator and discriminator circuits will be opposite.

Another important object of this invention is, therefore, to provide a novel FM circuit utilizing a symmetrical modulating device thereby providing cancellation of even harmonics, greatly reducing distortion, and doubling the output voltage from the discriminator.

The present invention has particular utility in an FM system for reproducing recorded sound waves. One such FM system has been disclosed, for example, by Chester M. Sinnott in application Serial No. 459,375, filed September 23, 1942 and assigned to Radio Corporation of America. The particular Sinnott system is a single ended frequency modulation network employing a capacity pickup device of the ribbon type for the reproduction of sound recordings. In the Sinnott system, the frequency modulation network consists of an electron discharge tube which has one section thereof functioning as a high frequency oscillator of constant amplitude the frequency of which is deviated by variations in the capacity pickup. In the plate circuit of the tube, there are developed frequency modulated oscillations which are subsequently converted into audio modulated signals corresponding to the originally recorded audio signals by a frequency discrimination process.

By applying the generic method of my invention to the particular Sinnott system, or in general to any FM system of record reproduction, various advantages are secured. The advantages in my system result in reduction of the mass of the vibratory pickup system; reduction of even harmonics; reduction of wear on the record surface; and an increase in the amplitude of the audio output voltage. I have found that these advantages may be realized by employing an additional capacitative variation across the discriminator circuit. The additional capacity variation is effected by the same capacitative vibratory system which is utilized across the oscillator tank circuit. Furthermore, the dual capacity variations may be so correlated that the

changes in the oscillator frequency and the discriminator circuit resonance occur 180 degrees out of phase, whereby a push-pull frequency deviation effect is secured. Cancellation of even harmonics, reduction of inter-modulation and higher audio voltage output are immediately realized by such a system. The higher audio voltage output can be employed to advantage because the size of the pickup condenser plates can be reduced.

Accordingly, it may be stated that it is another object of my present invention to provide an FM network for use with a simple, specially-designed capacity pickup device which is adapted to reproduce either lateral or vertically cut records, a frequency modulated signal being provided the frequency deviation of which is the cumulative effect of oscillator and discriminator frequency variation in push-pull relation whereby the various aforementioned advantages may be secured.

In a pickup, it is most important to keep the mass of the vibratory system as low as possible. This raises the frequency of the peak and reduces the mechanical impedance, thereby permitting a reduction of needle pressure and the accompanying reduction of surface noise. Accordingly, it may be stated that it is another important object of my invention to provide an improved capacity pickup device wherein the stylus supporting wire acts as the center plate of a push-pull condenser working into a balanced, or push-pull, FM oscillator-discriminator network whereby the mass of the pickup is reduced to a minimum, since nothing else would be mechanically coupled to the stylus except its own support; and the supporting wire being small in cross-section so that no extra mass would be added in transforming the mechanical vibrations to electrical signals at corresponding frequencies.

Yet another object of my present invention is to provide an improved mounting for the pickup device whereby the coupling elements between the pickup and the supporting arm therefor will serve both as electrical and mechanical coupling elements therebetween to thereby eliminate extraneous parts, the mechanical coupling also having compliance to flexibly mount the pickup on the arm.

Still other objects of my invention are to improve generally the simplicity and efficiency of record reproducing equipment of the FM type, and more especially to provide a high fidelity, low cost and low distortion record reproducer system which is easily manufactured and readily assembled.

The novel features which I believe to be characteristic of my invention are set forth in particularity in the appended claims; the invention itself, however, as to both its organization and method of operation, will best be understood by reference to the following description, taken in connection with the accompanying drawings, in which

Figure 1 is a side elevation of one form of pickup device according to the present invention with one of the stationary condenser plates omitted for the sake of clearness;

Figure 2 is a bottom plan view of the pickup;

Figure 3 is a detail view showing particularly the stylus supporting wire which constitutes the movable condenser plate or electrode;

Figure 4 is a section along line IV—IV of Fig. 3;

Figure 5 shows the circuit diagram of a preferred reproducing circuit according to the pres-

ent invention and employing my improved pickup device;

Figure 6 is a bottom plan view of a modified form of pickup device according to the present invention and employing an improved form of mounting; and

Figure 7 is a central sectional view of the latter form of pickup device shown connected to a mounting therefor.

Referring more particularly to the drawings, wherein similar reference characters designate corresponding parts throughout, there is shown, in Figs. 1 to 4, a pickup supporting arm 1 to which is connected a capacity pickup device 3 by means of one or more spring plates 5. The pickup 3 comprises a block 7 of "Bakelite" or other suitable dielectric material to the front end of which is secured a brass block 9 by means of a screw or the like 11. A steel wire 13 is secured to and extends from the bottom of the block 9, the wire 13 terminating at its free end in a loop or eye 15 in which a needle or stylus 17 is mounted for cooperation with a phonograph record. The wire 13 and its needle 17 may be of the type disclosed in the Hasbrouck Patent No. 2,326,460, the stylus supporting wire 13 being preferably rectangular in cross section, as clearly shown in Fig. 4. Preferably, the wire 13 is ground flat along its vertical plane on both sides along its entire length to a thickness of about 0.008 inch. By way of illustration, it may be pointed out that the vertically extending portion of the supporting wire 13 in Fig. 3 may have a dimension of 0.09 inch, the distance between the bend in the wire and the sapphire point may be equal to 0.13 inch, and the sapphire point 17 may have a radius of 0.0028 inch. Also, as shown in Fig. 4, the long cross-sectional dimension of the wire 13 may be 0.014 inch, while the short dimension thereof may be 0.008 inch.

Also mounted on the supporting block 7 in spaced and electrically insulated relation to each other are a pair of rod-like or bar-like, stationary, condenser plates 19 and 21, as best seen in Fig. 2. The plates 19 and 21 are substantially parallel to each other and are disposed one on each side of the stylus wire 13. Each of the fixed or stationary condenser plates 19 and 21 is spaced a distance preferably of about 0.003 inch to 0.005 inch from the stylus wire 13. The two fixed condenser plates 19 and 21 form the two outside plates of a balanced condenser, while the movable condenser plate or wire 13, which is connected to ground, constituted the movable electrode of the condenser.

The spring plates 5 permit movement of the pickup device 3 in a vertical direction relative to the supporting arm 1. The purpose of this compliance is to prevent damage to the pickup head when it is accidentally dropped on a record. The arm 1 consists of a conventional U-shaped channel but has a supporting shield 23 running lengthwise thereof and forming two separate channels therein. The two leads 25 and 27 from the pickup head 3, which, with the shield 23, may be regarded as radio frequency transmission lines, are connected to the fixed plates 19 and 21, respectively, and are placed inside of the two corresponding channels in the arm 1 and are supported centrally therein by means of small blocks of suitable damping material, preferably of the type and in a manner more particularly disclosed in the copending application of C. M. Sinnett, Serial No. 414,305, filed October 9, 1941, now Patent No. 2,376,456, granted May 22, 1945. This is done so as to permit the least capacity and maxi-

imum shielding between the transmission lines. Damping of the vibratile stylus wire 13 may be obtained by means of a "Viscoloid" damping block 29 in order to suppress torsional resonance of the stylus wire.

A pickup device such as described above may be employed in any suitable FM circuit, the capacity changes in the condensers 19, 13 and 13, 21 which result from vibration of the wire 13 in response to a record groove being utilized to vary the frequency of a tuned oscillator circuit, and the output of the oscillator being applied to the resonant input of a suitable discriminator which converts the frequency variable oscillations into amplitude variable oscillations in known manner. One such circuit is shown, by way of illustration, in Fig. 5 and comprises a tube 31 of the 6SF7 type or any other suitable type capable of serving as an electron coupled oscillator, discriminator and detector. The tube 31 is provided with a cathode 32, an oscillator grid 33, an oscillator anode 34 which is the screen grid of the tube, a suppressor 35, a plate 36 and an auxiliary anode 37. The auxiliary anode 37 cooperates with the cathode 32 to provide the necessary rectification while the suppressor 35 acts as an electrostatic shield between the plate 36 and the other elements of the tube.

The cathode 32 of the tube 31 is grounded and connected to a low tap on an oscillator coil 38, preferably one which has an adjustable core of comminuted iron and is therefore of the variable inductance type. The control grid 33, which functions as the oscillator section grid, is connected through a D.-C. blocking condenser 40 to the high potential side of the coil 38 and to one of the fixed plates of the pickup device 3 (for example, the plate 19). The second fixed plate 21 of the device 3 is connected through a D.-C. blocking condenser 42 to the output plate 36 of the tube 31. The plate 36 is also connected to the high potential side of a discriminator coil 44 which, like the coil 38, has a core of comminuted iron and is of the variable inductance type. However, if the turns in the coils 38 and 44 are properly adjusted, it is possible to have only one of them variable, preferably the oscillator coil 38. The coil 44 can have a slightly higher inductance by addition of one or two turns, so that its tuning will coincide with the tuning of the coil 38 with its iron core half way in. This affords enough range to position the oscillator mean frequency on the discriminator resonance curve in its proper relation thereto.

The movable plate or stylus wire 13 of the pickup device 3 is connected through a lead 45 to the grounded, negative terminal of a suitable direct current energizing source. The positive terminal of this source may be at +300 volts and is connected through a resistor 48 to the screen grid 34, the low potential end of the coil 44 being connected to the positive terminal of the +300 volt source and by passed to ground by a capacitor 46. The screen grid 34, which functions as an oscillator plate or anode, feeds into the lower part of the coil 38 through a coupling capacitor 50. The third grid 35 of the tube 31 is connected back to the lead 45 which is grounded. A resistor 52 connected between the cathode 32 and the auxiliary anode 37 constitutes the detector resistor load.

The cathode 32, the grid 33 and the anode electrode 34 of the tube 31 constitute the local oscillator section of the system. The coil 38 is resonated to a mean or center frequency F_0 which

may be in the range of about 15 mc. to 60 mc. per second and which is to be deviated in accordance with the amplitude of the modulation frequencies. The deviation range of the mean frequency is dependent on the capacity change of the condenser 13, 19 and the mean frequency employed. The factors governing the mean frequency of the oscillator are more fully set forth in my above-mentioned copending application and are not believed to require further discussion here. In any case, it will be apparent that the condenser 13, 19 is connected across the oscillator coil 38, while the condenser 13, 21 is shunted across the discriminator coil 44. The discriminator coil should be slightly off-tune from the oscillator mean frequency, either above or below the latter, and the oscillator mean frequency should be tuned to the middle portion of a linear part of the discriminator curve side.

A pickup device as described above and connected to an oscillator and a discriminator as shown in Fig. 5 constitutes a balanced transducer for varying the tuning of the oscillator and the discriminator in opposite directions or phase relations simultaneously. In operation, variations in the capacity of the condensers 13, 19 and 13, 21 produce corresponding variations in tuning of the oscillator and the discriminator and will cause shifting of the oscillator frequency in a direction opposite to that of the discriminator resonance peak frequency. Since the oscillator and the discriminator are coupled electronically in the tube 31, the frequency variations of the oscillator will be applied to the discriminator to provide FM oscillations in the plate circuit of the tube. The discriminator coil 44 feeds its output energy through a coupling condenser 54 to the diode anode 37 of the rectifier or detector section of the tube 31, and thus an audio signal results.

A radio frequency choke coil 56 is inserted to prevent the RF voltage from being present in the output circuit, which would be of audio frequency in the case of phonograph record reproduction. As pointed out above, the resistor 52 is the detector load resistor. The audio output energy may be amplified and reproduced in any suitable way.

In Figs. 6 and 7, I have shown a somewhat modified form of pickup device and mounting therefor constructed according to the present invention. Here, the stationary plates of the condenser are constituted by a pair of conductive inserts 19a and 21a in a molded supporting block 7a of suitable electrical insulating material, such as phenol-formaldehyde resin while the wire 13 is secured by soldering or in any other suitable manner to a third conductive insert 9a in the block 7a. To the inserts 19a, 9a and 21a are spot welded or otherwise suitably secured spring steel coupling members 60, 61 and 62, respectively, the members 60, 61 and 62 being secured to their respective condenser electrode plates prior to the molding of the block 7a, of course, and extending from the block 7a, as shown. A molded mounting member or holder 63 includes three terminal inserts 64, one for each of the springs 60, 61 and 62. The spring members 60, 61 and 62 are placed against the block 63 in contact with their respective terminal members 64, as clearly shown in Fig. 7, and they are held against the terminals 64 by means of a clamping plate 65 of suitable electrical insulating material, which may be similar to the material of the supporting block 7a, and one or more screws 66. The terminals 64 provide an

external connection of the pickup condenser plates to a suitable transmission line of the type shown in Fig. 2, for example. The advantage offered by this form of my invention is that the spring members 60, 61 and 62 serve both as supports for the pickup device and electrical coupling members to the electrode plates thereof, while at the same time providing a compliant coupling between the pickup 3 and the support or holder 63 which may or may not be a part of the pickup arm proper. With this form of plug-in type mounting, it is apparent that the pickup device may be easily and quickly removed from the holder 63 by merely loosening the screws 66 and replaced by another one which is suitable for a particular requirement.

Although I have shown and described two forms of my present invention, it will undoubtedly be obvious to those skilled in the art that many other modifications thereof, as well as variations in those herein described, are possible. For example, instead of making the center plate or wire 13 the movable element, it may be held stationary and the needle 17 mounted on an insulated cross-piece which connects the lower or outer ends of the plates 19 and 21, the latter then being made of resilient material and constituting the movable elements of the two condensers. Moreover, while I have shown, for the purpose of illustration only, a pickup device especially suitable for operation on a lateral cut type of record, it will undoubtedly be apparent to those skilled in the art that the pickup may be arranged for operation with hill and dale records as well. Other changes of a similar nature are also possible. I therefore desire that my invention shall not be limited except insofar as is made necessary by the prior art and by the spirit of the appended claims.

I claim as my invention:

1. A phonograph record signal translating device comprising, in combination, a support, a pair of conductive members carried by said support, said members extending downwardly from and to one side of said support in physically spaced and electrically insulated relation to each other, a third conductive member carried by said support in electrically insulated relation to each of said pair of members, said third member also extending downwardly from and to one side of said support between and in spaced relation to each of said pair of members and having a freely suspended end terminating in a loop, and a needle mounted in said loop for cooperation with a phonograph record, said three members cooperating to provide a pair of capacitor components, and said third member being movable laterally relative to each of said pair of members in response to movement of said needle by a record to thereby vary the capacities of said components simultaneously and in opposite phase.

2. A phonograph record signal translating device comprising, in combination, a support, a pair of conductive members carried by said support, and said members extending downwardly from and to one side of said support in physically spaced and electrically insulated relation to each other, a resilient element constituting a third conductive member carried by said support in electrically insulated relation to each of said pair of members, said resilient element also extending downwardly from and to one side of said support between and in spaced relation to each of said pair of members and terminating in a loop at one end, and a needle mounted in said loop for co-

operation with a phonograph record, said three members cooperating to provide a pair of capacitor components, and said resilient element being anchored at its opposite end whereby it is adapted to flex for movement relative to said pair of members in response to movement of said needle by the record to thereby vary the capacities of said components simultaneously in opposite phase.

3. In signal translating apparatus, the combination of an electro-mechanical transducer head including electro-conductive signal converting elements, a mounting for said transducer including terminal members, and means coupling said elements mechanically and electrically to said terminal members, said coupling means comprising the sole connection between said transducer and said mounting.

4. In signal translating apparatus, the combination of an electro-mechanical transducer head including electro-conductive signal converting elements, a mounting for said transducer including terminal members, and resilient means coupling said elements mechanically and electrically to said terminal members, said coupling means serving as the sole connection between said transducer head and said mounting, and the resilience of said coupling means affording a compliance therebetween.

5. In signal translating apparatus, the combination of a transducer head including a support, a pair of conductive elements carried by said support and constituting a first electrode unit, said elements extending from said support in physically spaced and electrically insulated relation to each other, a third conductive element carried by said support in electrically insulated relation to each of said pair of elements, said third element constituting a second electrode unit and extending from said support between

and in spaced relation to each of said pair of elements, said three elements cooperating to provide a pair of capacitor components and one of said units being movable laterally relative to the other of said units for varying the capacities of said components simultaneously and in opposite phase, a mounting for said transducer including a plurality of terminal members, one for each of said elements, and resilient means coupling said elements mechanically and electrically to said terminal members, said coupling means serving as the sole connection between said transducer head and said mounting, and the resilience of said coupling means affording a compliance therebetween.

6. In signal translating apparatus, the combination of a transducer head including a support, a pair of conductive elements carried by said support, said elements extending from said support in physically spaced and electrically insulated relation to each other, a third conductive element carried by said support in electrically insulated relation to each of said pair of elements, said third element extending from said support between and in spaced relation to each of said pair of elements, said three elements cooperating to provide a pair of capacitor components and said third element being movable laterally relative to each of said pair of elements for varying the capacities of said components simultaneously and in opposite phase, a mounting for said transducer including a plurality of terminal members, one for each of said elements, and resilient means coupling said elements mechanically and electrically to said terminal mem-

bers, said coupling means serving as the sole connection between said transducer head and said mounting, and the resilience of said coupling means affording a compliance therebetween.
